UNITED STATES PATENT OFFICE.

FRANK E. SMITH, OF TROY, NEW YORK, ASSIGNOR OF ONE-HALF TO E. AUGUSTUS DENNIN, OF TROY, NEW YORK.

STOPPING ATTACHMENT FOR PHONOGRAHS.

Application filed June 7, 1923. Serial No. 643,826.

Reference may be had to the accompanying drawings, and the reference characters marked thereon, which form a part of this specification. Similar characters refer to similar parts in the several figures therein.

This invention relates to means for automatically stopping the rotation of the turntable of a phonograph or the like at the end of the record-induced movement of the tone-arm of the instrument.

One object of the invention is to quickly stop the rotation of the turntable upon completing the reproduction of the record without materially retarding the speed of the turntable during the reproduction of any part of the record.

Another object of the invention is to automatically raise the needle from the record and impart a return movement to the tone-arm upon the completion of the reproduction of the record.

Other objects will appear in connection with the following description.

Fig. 1 of the drawings is a top plan view of a phonograph provided with my improved stop-mechanism showing the tone-arm at the limit of its outward or rearward movement.

Fig. 2 is a similar view showing the tone-arm at approximately the limit of its inward or forward movement.

Fig. 3 is a vertical section of the same taken on the broken line 3—3 in Fig. 1, viewed in the direction of the arrow.

Fig. 4 is a bottom plan view of a broken-away portion of the tone-arm and parts mounted thereupon.

Fig. 5 is a vertical cross-section taken through the tone-arm on the broken line 5—5 in Fig. 1.

Fig. 6 is a vertical section taken on the broken line 6—6 in Fig. 2 through the brake.

Fig. 7 is a vertical cross-section taken through the cam mechanism on the broken line 7—7 in Fig. 8.

Fig. 8 is a view in front elevation of the cam-mechanism showing the tone-arm-returning rod in cross-section in position to maintain the tone-arm in its braking position.

Fig. 9 is a similar view showing said rod in brake-releasing position.

Fig. 10 is a similar view showing said

rod about to enter the gate in the cam-mechanism.

Fig. 11 is a cross-section of the tone-arm-returning rod provided with an antifriction roller.

Referring to the drawings wherein the invention is shown in preferred form, 1 is the top or body of a phonograph upon which is rotatively mounted the usual turntable, 2, having a depending peripheral flange, 3.

The turntable has the usual spindle, 4, upon which is mounted the record, 5, to rotate with the turntable.

The instrument also has the usual goose-neck tone-arm, 6, upon the outer end of which a sound-box, 7, is mounted in the usual manner, said sound-box carries the usual needle, 8, engageable with the groove in the record.

The parts above described are found in the ordinary phonograph and further description thereof will be unnecessary.

In carrying out my invention in preferred form, I mount upon the top or body, 1, of the phonograph cam-mechanism including a pair of vertically disposed plates, 10 and 11, supported by a horizontal base-plate, 12, adjustably mounted upon the top, 1, by means of screws, 13, inserted through slots, 14, in said base-plate into said top, 1.

The plate, 10, is formed with a top surface, 15, which is approximately horizontal although preferably slightly inclined downwardly toward the entrance to a gate, 16, formed between said plates, 10 and 11.

The upper edge of the plate, 11, which forms the bottom of the gate, 16, is in the form of a cam inclined or curved downwardly and rearwardly from the entrance to the gate, and upwardly and rearwardly toward the exit from the gate.

The upper edge of the plate, 10, is inclined downwardly and rearwardly, that is, toward the exit from the gate as shown at 17.

Fixed upon the tone-arm, 6, is a bracket, 18, upon the outer end of which is a brake, 19, which can be carried into and out of engagement with the flange, 3, of the turntable by movement of the tone-arm.

Pivotedly mounted at 20, upon the under side of the tone-arm on an axis at right angles to the tone-arm is a rod, 21, extending along the under side of the tone-arm, the outer end of which rod is adapted to

engage the cam-mechanism formed by the plates, 10 and 11.

For convenience and to form a place for the rod, 21, the rod is passed through a vertical slot, 22, in the bracket, 18, in which slot the rod is adapted to play vertically.

A coil-spring, 23, tends to force the outer end of the rod, 21, downward.

In fixed relation to the rod, 21, on the 10 opposite side of the bearing, 20, from which the rod, 21, extends is a shorter rod, 24, the outer end of which extends beneath the sound-box, 7, said rod, 24, being adapted to engage and raise the sound-box and goose-neck, 25, when the outer end of the rod, 21, is depressed by the spring, 23.

The outer end of the rod, 21, is adapted to ride over the top edge or surface of the plate, 10, of the cam-mechanism and to 20 traverse the gate, 16, of the same.

The cam-mechanism is provided with a spring-latch, 26, adjacent to the exit from the gate, 16, which latch is adapted to yield to permit the rod, 21, to pass out of the 25 gate and then to support the rod at the lower end of the inclined surface, 17, on the plate, 10.

The operation of the device is as follows:

In the stopped position of the tone-arm, 30 6, the rod, 21, is at the lower end of the surface, 17, on the plate, 10, resting upon the latch, 26, as shown in Fig. 8, in which position the brake, 19, is in engagement with the flange, 3, of the turntable, preventing 35 rotation of the turntable as shown in Fig. 1; and the sound-box, 7, is supported by the rod or arm, 24, in a sufficiently elevated position to prevent the needle, 8, from engaging the record, 5, on the turntable.

40 To start the operation of the phonograph, the operator raises the sound-box with his hand, moves the tone-arm, 6, inwardly or forwardly as indicated by dotted lines in Fig. 1, until the needle is vertically above 45 the beginning of the groove in the record, 5.

This movement moves the brake, 19, out of engagement with the turntable as indicated by dotted lines in Fig. 1, whereupon 50 the turntable begins to rotate.

When the turntable has reached the proper speed, the operator lowers the sound-box to bring the needle into engagement with said groove. The movement of the tone-arm just referred to carries the rod, 21, upward over the surface, 17, and on to the surface, 15, of the plate, 10, as shown in Fig. 9.

60 The operation of the instrument then proceeds and as the needle traverses the groove in the record and the tone-arm, 6, moves forward or inwardly, the rod, 21, is carried along the surface, 15, on the plate, 10, until at approximately the time that the needle reaches the end of its grooved path, said rod

will be at the mouth of the gate, 16, in the position shown in Fig. 10.

Slight further movement of the needle and tone-arm then carries the rod, 21, into the mouth of the gate, 16, whereupon the 70 spring, 23, quickly forces the rod downward, said downward movement being converted into a traversing movement along the gate.

The movement of the rod, 21, and the tone-arm moves the brake, 19, into engagement with the turntable, the movement of the turntable thereby being frictionally imparted through the brake to the tone-arm and rod, 21, thus carrying the rod, 21, upward and out through the exit from the 75 gate and past the yielding latch, 26, which immediately springs back beneath the rod and prevents a return movement of the rod into the gate through the gate exit, the rod thus being again supported in the position 80 shown in Fig. 8.

This movement of the rod through the 85 gate is transmitted to the tone-arm, 6, to move the same rearwardly or outwardly from approximately the position shown in Fig. 2, to the position shown in Fig. 1.

The movement thus imparted to the tone-arm, 6, carries the brake, 19, into engagement with the turntable as shown in Fig. 1, and stops the operation of the turntable. 90

The initial engagement of the brake, 19, with the turntable is not sufficient to instantly stop the rotation of the turntable with the result that the rotative movement of the turntable is transmitted through the 100 brake to the tone-arm, causing the rod, 21, to be forced upwardly at the rear end of the gate past the latch, 26, at approximately which time the brake acts with sufficient force to stop the turntable. 105

The downward movement imparted to the rod, 21, by the spring, 23, as above described throws the rod, 24, into engagement with the sound-box, 7, raising the same to a greater degree above the record than shown in Fig. 3, and as the return movement of the tone-arm caused by the mechanism above described is very quickly accomplished the needle will have passed beyond the edge of the record before the sound-box 110 needle can have any substantial downward movement.

However, the downward incline, 17, on the plate, 10, may be, and preferably is, such that when the rod, 21, is resting at the bottom thereof upon the latch, 26, the needle will still be supported above the level of the record. 115

If desired, the rod, 21, may be provided with an antifriction roller, 28, adapted to engage the cam mechanism formed by the plates, 10 and 11. 120

What I claim as new and desire to secure by Letters Patent is—

1. In a talking machine and in combina- 125

tion, a turntable; a tone-arm pivotally mounted upon a vertical axis; a vertically movable needle-holder mounted upon the tone-arm; a rod extending longitudinally of the tone-arm and pivotally connected at one end therewith upon a horizontal axis at right angles to the tone-arm; a spring for depressing said rod; cam-mechanism having a support over which said rod rides during the forward movement of the tone-arm and provided with a gate extending downwardly and rearwardly from the inner end of said support; and means for automatically raising the needle-holder by the depression of the rod.

2. In a talking machine and in combination, a turntable; a tone-arm pivotally mounted upon a vertical axis; a vertically movable needle-holder mounted upon the tone-arm; a brake carried by the tone-arm into and out of engagement with the turntable; a rod extending longitudinally of the tone-arm and pivotally connected at one end therewith upon a horizontal axis at right angles to the tone-arm; a spring for depressing said rod; cam-mechanism having a support over which said rod rides during the forward movement of the tone-arm and provided with a gate extending downwardly and rearwardly from the inner end of said support, and upwardly and rearwardly toward the outer end of said support; and means for automatically raising the needle-holder by depression of said rod, said brake being engageable with said turntable to carry said rod upwardly through the rear end of said gate toward said support.

3. In a talking machine and in combination, a turntable; a tone-arm pivotally mounted upon a vertical axis; a vertically movable needle-holder mounted upon the tone-arm; a brake carried by the tone-arm into and out of engagement with the turntable; a rod extending longitudinally of the tone-arm and pivotally connected at one end therewith upon a horizontal axis at right angles to the tone-arm; a spring for depressing said rod; cam-mechanism having a support over which said rod rides during the forward movement of the tone-arm and provided with a gate extending downwardly and rearwardly from the inner end of said support, and upwardly and rearwardly toward the outer end of said support; a rod-supporting latch adjacent to the exit from said gate; and means for automatically raising the needle-holder by depression of said rod, said brake being engageable with said turntable to carry said rod upwardly through the rear end of said gate toward said support.

4. In a talking machine and in combination, a turntable; a tone-arm pivotally mounted upon a vertical axis; a vertically movable needle-holder mounted upon the tone-arm; a brake carried by the tone-arm into and out of engagement with the turntable; a rod extending longitudinally of the tone-arm and pivotally connected at one end therewith upon a horizontal axis at right angles to the tone-arm; a spring for depressing said rod; cam-mechanism having a support over which said rod rides during the forward movement of the tone-arm and provided with a gate extending downwardly and rearwardly from the inner end of said support, and upwardly and rearwardly toward the outer end of said support; a rod-supporting latch adjacent to the exit from said gate; and means for automatically raising the needle-holder by depression of said rod, said brake being engageable with said turntable to carry said rod upwardly through the rear end of said gate toward said support.

5. In a talking machine and in combination, a turntable; a tone-arm pivotally mounted upon a vertical axis; a vertically movable needle-holder mounted upon the tone-arm; a brake carried by the tone-arm into and out of engagement with the turntable; a rod extending longitudinally of the tone-arm and pivotally connected at one end therewith upon a horizontal axis at right angles to the tone-arm; a spring for depressing said rod; cam-mechanism having a support over which said rod rides during the forward movement of the tone-arm and provided with a gate extending downwardly and rearwardly from the inner end of said support, and upwardly and rearwardly toward the outer end of said support, the exit from said gate being lower than the entrance to the gate; a rod-supporting latch adjacent to the exit from said gate; and means for automatically raising the needle-holder by depression of said rod, said brake being engageable with said turntable to carry said rod upwardly past said latch.

6. In a talking machine and in combination, a turntable; a tone-arm pivotally mounted upon a vertical axis; a vertically movable needle-holder mounted upon the tone-arm; a rod extending longitudinally of the tone-arm and pivotally connected at one end therewith upon a horizontal axis at right angles to the tone-arm; a spring for depressing said rod; cam-mechanism having a support over which said rod rides during the forward movement of the tone-arm and provided with a gate extending downwardly and rearwardly from the inner end of said support, and a member connected with said rod in fixed relation thereto, and actuated by the downward movement of said rod to engage and raise the needle-holder.

7. In a talking machine and in combina-

- tion, a turntable; a tone-arm pivotally mounted upon a vertical axis; a vertically movable needle-holder mounted upon the tone-arm; a brake carried by the tone-arm into and out of engagement with the turntable; a rod extending longitudinally of the tone-arm and pivotally connected at one end therewith upon a horizontal axis at right angles to the tone-arm; a spring for depressing said rod; cam-mechanism having a support over which said rod rides during the forward movement of the tone-arm and provided with a gate extending downwardly and rearwardly from the inner end of said support, and upwardly and rearwardly toward the outer end of said support; and a member connected with said rod in fixed relation thereto, and actuated by the downward movement of said rod to engage and raise the needle-holder, said brake being engageable with said turntable to carry said rod upwardly past said gate toward said support.
8. In a talking machine and in combination, a turntable; a tone-arm pivotally mounted upon a vertical axis, a vertically movable needle-holder mounted upon the tone-arm; a brake carried by the tone-arm into and out of engagement with the turntable; a rod extending longitudinally of the tone-arm and pivotally connected at one end therewith upon a horizontal axis at right angles to the tone-arm; a spring for depressing said rod; cam-mechanism having a support over which said rod rides during the forward movement of the tone-arm and provided with a gate extending downwardly and rearwardly from the inner end of said support, and upwardly and rearwardly toward the outer end of said support; a rod-supporting latch adjacent to the exit from said gate; and a member connected with said rod in fixed relation thereto, and actuated by the downward movement of said rod to engage and raise the needle-holder, said brake being engageable with said turntable to carry said rod upwardly past said latch.
9. In a talking machine and in combination, a turntable; a tone-arm pivotally mounted upon a vertical axis; a vertically movable needle-holder mounted upon the tone-arm; a brake carried by the tone-arm into and out of engagement with the turntable; a rod extending longitudinally of the tone-arm and pivotally connected at one end therewith upon a horizontal axis at right angles to the tone-arm; a spring for depressing said rod; cam-mechanism having a support over which said rod rides during the forward movement of the tone-arm and provided with a gate extending downwardly and rearwardly from the inner end of said support, and upwardly and rearwardly toward the outer end of said support, the exit from said gate being lower than the entrance to the gate, to the gate; a rod-supporting latch adjacent to the exit from said gate; and a member connected with said rod in fixed relation thereto, and actuated by the downward movement of said rod to engage and raise the needle-holder, said brake being engageable with said turntable to carry said rod upwardly past said latch.
10. In a talking machine and in combination, a turntable; a tone-arm pivotally mounted upon a vertical axis; a vertically movable needle-holder mounted upon the tone-arm; a brake carried by the tone-arm into and out of engagement with the turntable; a rod extending longitudinally of the tone-arm and pivotally connected at one end therewith upon a horizontal axis at right angles to the tone-arm; a spring for depressing said rod; cam-mechanism having a support over which said rod rides during the forward movement of the tone-arm and provided with a gate extending downwardly and rearwardly from the inner end of said support, and upwardly and rearwardly toward the outer end of said support, the exit from said gate being lower than the entrance to the gate, to the gate; a rod-supporting latch adjacent to the exit from said gate; and a member connected with said rod in fixed relation thereto, and actuated by the downward movement of said rod to engage and raise the needle-holder, said brake being engageable with said turntable to carry said rod upwardly past said latch.
11. In a talking machine and in combination, a turntable; a tone-arm pivotally mounted upon a vertical axis; a vertically movable needle-holder mounted upon the tone-arm; a brake carried by the tone-arm into and out of engagement with the turntable; a rod extending longitudinally of the tone-arm and pivotally connected at one end therewith upon a horizontal axis at right angles to the tone-arm; a spring for depressing said rod; cam-mechanism having a support over which said rod rides during the forward movement of the tone-arm and provided with a gate extending downwardly and rearwardly from the inner end of said support; and means for automatically raising the needle-holder, by depression of said rod, said tone-arm having a vertical slideway for said rod at a point between the pivotal axis of the rod and said cam-mechanism, said brake being engageable with said turntable to carry said rod upwardly through the rear end of said gate towards said support.
12. In a talking machine and in combination, a turntable; a tone-arm pivotally mounted upon a vertical axis; a vertically movable needle-holder mounted upon the tone-arm; a brake carried by the tone-arm

into and out of engagement with the turntable; a rod extending longitudinally of the tone-arm and pivotally connected at one end therewith upon a horizontal axis at right angles to the tone-arm; a spring for depressing said rod; cam-mechanism having a support over which said rod rides during the forward movement of the tone-arm and provided with a gate extending downwardly and rearwardly from the inner end of said support, and upwardly and rearwardly toward the outer end of said support, the exit from said gate being lower than the entrance to the gate, the outer end of said sup-

port forming a cam surface extending downwardly and outwardly to the exit from the gate; a rod-supporting latch adjacent to the exit from said gate; and means for automatically raising the needle-holder by depression of said rod, said tone-arm having a vertical 20 slideway for said rod at a point between the pivotal axis of the rod and said cam-mechanism, said brake being engageable with said turntable to carry said rod upwardly past said latch.

In testimony whereof, I have hereunto set my hand this 25th day of November, 1922.

FRANK E. SMITH,
